GRILLE-GUARDED RADIATOR SHELL
FRONT

Lee B. Green, Lakewood, Ohio, assignor to The
Globe Machine & Stamping Company, Cleve-
land, Ohio, a corporation of Ohio

Application June 29, 1934, Serial No. 733,101

9 Claims. (Cl. 293—54)

My invention relates to a guard of the general class in which parallel guard bars effectively span an opening in a member which supports them.

When used on the radiator shell fronts of engine-driven trucks, such guards have commonly been composed of solid steel bars spanning a steel frame which in turn is bolted to the front of the radiator shell. Thus constructed, the amount of metal required for both the guard bars and the frame, together with the manufacturing of the frame and rigidly connecting the bars to it, involve an undesirable high cost. Moreover, the generally rectangular lines of such a guard do not harmonize with the general design of the radiator shell on which this guard is mounted, and particularly not when the radiator shell and hood have the curved lines now generally found on the entire exterior portions of the more artistically designed auto trucks.

However, the just recited practice of disposing the bars of the guard forwardly of the front of the radiator shell affords the advantage that these bars more adequately prevent objects in front of the truck from damaging what is behind the radiator shell front; also, that the guard bars may be of considerably greater length than the spread of the said opening longitudinally of the said bars, thereby guarding against an indenting of the part of the shell front which borders its air-admitting opening.

For modern passenger automobiles, the guard for the frontal opening of the radiator shell usually is a socalled grille consisting of cross-connected bars (or rearwardly open U-sectioned blades), which bars or blades present their ends behind the shell front. Thus disposed, the guard bars or blades do not adequately protect the portions of the shell front adjacent to the said frontal opening against impact, and their said disposition emphasizes the shape of the frontal opening, which shape may not harmonize with the general design of the car front when this opening is formed for distributing air effectively to the entire radiator core behind the shell front.

Moreover, if the design of the car front is such that the frontal opening is of considerably less height than the shell front, an unduly large upper portion of this car front may not be influenced by the appearance of a grille to a sufficient extent to afford the desired ornamental appearance. In addition, the use of many scores of blades in such a grille makes them present such a thin-lined effect as to be out of harmony with the use of broad panel effects often desired in the general design of the car.

My present invention aims to overcome the just recited disadvantages of an interiorly mounted grille or guard, while also avoiding the high cost of forging solid bars and the unornamental appearance of a frontally exposed bar frame. In addition, my invention aims to provide a guard in which the constituent (generally parallel) bars may extend at each end to any desired distance beyond the frontal shell opening across which they effectively extend, and in which each such bar can be cheaply constructed of a U-section from sheet metal without having it present unsightly and dirt-admitting ends.

Furthermore, my invention aims to provide simple means for fastening such guard bars to the shell front without the use of cross-connecting members, and aims to provide guard bars which will readily permit a cleaning of the adjacent parts of the car front after mud has been splashed on it.

Still further and also more detailed objects will appear from the following specification and from the accompanying drawings, in which

Fig. 1 is a perspective view of a frontal panel portion of an automobile radiator housing in which the air-admitting opening and parts adjacent thereto are guarded in accordance with my invention.

Fig. 2 is an enlarged section taken along the line 2—2 of Fig. 1.

Fig. 3 is an enlarged front elevation of one of the guard members.

Fig. 4 is a rear elevation of a generally straight guard member of the same type, including the anchoring members mounted in it.

Fig. 5 is an enlarged section taken in the medial longitudinal plane of a straight guard member (as along the line 5—5 of Fig. 3) and through portions of a panel to which this member is fastened.

Fig. 6 is a rear view of the lower part of the guard member of Fig. 5.

Fig. 7 is a rear perspective view of the upper part of the guard member of Fig. 6, showing this before the anchoring member is mounted in it.

Fig. 8 is a perspective view of the channel strip from which the guard member of Fig. 5 was formed, with a dotted showing of the approximate line along which an end of this channel strip was cut off before forming this end to the shape shown in Fig. 7.

Fig. 9 is a vertical section through a portion of a radiator shell front in which the opening is bordered by a rearwardly offset flange to which

the end portions of the guard members are fastened.

Fig. 10 is a fragmentary section allied to Fig. 9, showing a guard member having its end portions projecting beyond the portions fastened to the shell front.

Fig. 11 is an enlarged rear perspective view of the upper end of the guard member of Fig. 10, and Fig. 12 is a reduced plan view of the sheet metal blank from which the sheet metal part pictured in Fig. 11 was formed.

Fig. 13 is a section, allied to the upper portion of Fig. 5, showing an alternative shaping of an end portion of my hollow guard member, and 15 the fastening of this blade end to a panel front.

Fig. 14 is a reduced rear perspective view of the hollow guard end part shown in Fig. 13.

In carrying out my invention after the manner of Figs. 3 to 7, I first form simple metal strips 20 of suitable uniform width to a U-shaped channel section, such as that of Fig. 8, and cut these to lengths sufficiently longer than a proposed hollow guard member to allow for the forming of the closed end as shown in Fig. 7. Then I shear 26 each end of such a cut channel strip diagonally from each side thereof—as for example along the dotted cut line C in Fig. 8—and thereafter deform that end (by dies readily made by any die-maker) to a shape such as that shown in Fig. 7, 30 namely one in which the formerly pointed end part of the cut channel strip is deformed to a hollow shape approximating a quarter of a flattened sphere, and in which the free edges 1 of this end portion are parallel to and offset rearwardly from the surface in which edges 2 of the major portions of the channel webs W are disposed.

Then I slide into each such hollow end a fastening member consisting of a plate 3 (Fig. 5) 40 having a bolt shank 4 extending through and projecting from it and having the head 5 of the bolt fastened to the said plate (as by a brazing 6). The plate 3 desirably is of a contour fitting the rear end of the said hollow end part E and 45 desirably also presents its rear face flush with the edges 1 (Fig. 7) and this plate is then fastened to the said hollow end part, as by a brazing 7.

Thus completed, each guard member G has 50 a bolt shank projecting rearwardly from it, so that the ends of this guard member can speedily be fastened to a panel P provided with perforations 9 for receiving the bolt shanks, but nuts N each screwed on one of the bolt shanks, desirably with a lock washer 8 between the nut and the rear face of the panel. Since the needed 55 perforations in the panel P are easily punched, the entire assembly is speedy and inexpensive.

Moreover, the channel strips S can readily be 60 rolled or otherwise formed for curving them to any desired forward convexity (as in Fig. 2) or concavity (as in Fig. 9) according to the appearance desired for the guard. The guard members G for a complete guard may extend for various distances at either end beyond the aperture A which is to be guarded, as shown in Fig. 1. Some of the guard members or blades may also be disposed laterally outside this aperture as also 65 shown in the same figure, so as to guard the shell front at each side of the panel opening A. Consequently, the contour of the guard as a whole may be considerably different from that of the 70 said aperture, thereby cooperating with the forward projecting of the guard members in de-

tracting a viewer's attention both from the contour of the said aperture and from what is behind the apertured panel.

Moreover, the closed end portions of each guard member afford added rigidity for it adjacent to its fastenings, and the U-section of the major portion of each guard member strongly resists its being flexed, so that I can effectively employ a much smaller number of guard members than the heretofore commonly used grille blades. 10

In practice, my closed-end channel-sectioned guard members may be used for many purposes even without having each end portion thereof projecting rearwardly beyond the rear edges of the main part of that member, as shown for example by Figs. 13 and 14. However, I preferably form either the guard members, or the panel portions to which they are fastened, so as to afford a spacing which will more readily permit any accumulated mud or the like to be washed off, this being particularly advisable when my hollow guard members are used on automobiles. 15

Thus, it will be obvious that any mud which has been splashed into the hollow lower end E¹ of Fig. 2 can readily be washed out by a stream 25 of water directed into the space s immediately above it. To facilitate this cleaning still more, and also to present a somewhat different ornamental appearance, I may make my channels from strips having each end portion thereof 30 blanked initially as shown in Fig. 12, so as to present laterally opposite projections b between the major part B of the strip and the extreme end portion which is to be cut to a point (along the dotted lines C) before that end portion is 35 deformed to the shape shown in Fig. 14.

By proceeding in this manner and fastening each needed bolt 4 to a rectangular punching 31, inserted between and brazed to two adjacent projections b, I can readily produce the form of 40 my guard member shown in Figs. 10 and 11, in which each anchoring provision is spaced from the adjacent hollow end so that water can readily be flushed through the interior of the entire blade for the entire length of the latter. 45

However, while I have heretofore described my invention in connection with embodiments including numerous desirable details of construction and arrangement, I do not wish to be limited in these respects, since many changes might 50 be made without departing either from the spirit of my invention or from the appended claims.

I claim as my invention:

1. A guard blade of rearwardly open U-section having a uniform section in its major portion, both U-webs of the blade being uniformly widened in a relatively short part of each end portion of the blade so as to dispose the rear edges of the webs in the said short blade parts in a surface spaced rearwardly from the common surface in which the rear edges of both U-webs of the said major portion of the blade are disposed. 55

2. A guard member for a guard of the class recited, comprising a guard blade as per claim 1, and two anchoring elements each mounted between the rear edge portions of one of the said relatively short parts of the blade. 60

3. A grille blade of rearwardly open U-section closed at both ends, and two anchoring elements 65 respectively mounted within and secured to the two end parts of the blade, each of the said anchoring elements having its rearward face in a common surface with the rear edges of blade portions contiguous to that anchoring element. 70

4. As a constituent for a guard in which parallel blades extend in front of an apertured supporting member and effectively across the aperture in the said member, a grille blade of rearwardly open U-section closed at both ends and having opposed rearward extensions on both of its blade webs, the said extensions being spaced from each other by a distance greater than the spread of the aperture; and two anchoring elements each disposed between and secured to one pair of the said opposed blade-web extensions.

5. A grille blade of rearwardly open U-section having each end portion thereof decreasing in the depth of its U-formation to zero at the end of the blade, the U-webs of the blade being uniform in the major part of the blade but widened in a relatively short blade portion near one end of the blade so that these short blade portions present their rear edges farther rearward than the rear edges of the parts of the blade webs between the said short portions; and two fastening elements each mounted between the rear edge parts of the said short blade portions and presenting rear faces flush with the rear edges of the webs of the short blade portions.

6. A generally U-sectioned sheet metal grille blade comprising a major portion of uniform and rearwardly open U-section, and two end portions respectively merging into the two ends of the said major portion; each end portion of the blade decreasing gradually in the depth of its U-formation toward the extreme end of the blade so as to afford a closed end for the blade, and each of the said end portions presenting its rear edge in a surface rearward of the common surface of the rear edges of the U-webs of the parts of the blade between the said end portions.

7. The combination with a radiator shell front having an air-admitting opening, of grille blades

of rearwardly open U-section extending across the said opening each presenting its two end portions respectively in front of parts of the said shell front at opposite sides of the said opening; and pairs of anchoring members respectively associated with the said several blades; each anchoring member comprising a first part housed by and secured to one of the said end portions of the blade, a stem part extending rearwardly from the aforesaid part through the radiator shell front, and a third part attached to the stem part and bearing against the rear face of the radiator shell fronts.

8. A radiator shell front and grille combination as per claim 7, in which the said first part of each of the said anchoring members has its rear face flush with the rear edge portions of the part of the blade which houses the said first part.

9. The combination with a radiator shell front having an air admitting opening, of parallel blades of rearwardly open U-section extending across the said opening; each blade presenting its two end parts respectively in front of parts of the radiator shell front at opposite sides of the said opening; each such end part having the rear edges of its U-webs in a portion of its said end part offset rearwardly from the common surface in which the major part of the rear edges of its U-webs are disposed, and having these rearwardly offset web edge portions engaging the said shell front so as to space other portions of the rear web edges of the blade forwardly from the shell front; two anchoring elements respectively mounted in the said rearwardly offset portions of its two end parts, and two means extending through the shell front for respectively fastening the said anchoring elements to the shell front.
